UNITED STATES PATENT OFFICE.

WILMOT E. CROZIER, OF OSCEOLA, NEBRASKA.

BOTTLE.

1,424,558.

Specification of Letters Patent. Patented Aug. 1, 1922.

Application filed August 29, 1921. Serial No. 496,452.

To all whom it may concern:

Be it known that I, WILMOT E. CROZIER, a citizen of the United States, residing at Osceola, in the county of Polk and State of Nebraska, have invented certain new and useful Improvements in Bottles, of which the following is a specification.

This invention relates to bottles, the primary object of which is to produce a bottle which would be impractical to refill thereby discouraging the spurious practice of refilling the bottle with an inferior material for resale as the product of the original manufacturer.

Other objects of the invention are to provide a bottle which will be simple in construction and inexpensive to manufacture; to provide a bottle from which the contents may be quickly, conveniently and completely dispensed; to provide a bottle from which the contents may be dispensed in different volumes; and to provide a bottle which may be quickly opened without the use of extraneous means.

The above and other objects of this invention will be in part described and in part understood from the following description of the present preferred embodiment of the invention taken in connection with the accompanying drawings wherein:-

Fig. 1 is a fragmentary vertical sectional view of a bottle constructed in accordance with this invention.

Fig. 2 is a side elevational view thereof showing one side of the neck.

Fig. 3 is a similar view showing the opposite side of the neck and

Fig. 4 is a cross sectional view taken on the line 4—4 of Fig. 1 looking in the direction of the arrow.

In use of this invention, it is immaterial what type of body is used since it may be of any desired configuration, thickness, color, etc., without having any bearing whatsoever on the device of this invention. Consequently, only a very small portion 5 of the body of the bottle is shown in the drawings having issuing therefrom a neck generally designated 6. Preferably the body and neck 50 of the bottle are "blown" simultaneously, the mold being so constructed that the outer end 7 of the neck will be closed and preferably of a semi-spherical configuration. The neck may be of any desired exterior configuration, it being shown in Fig. 4 of the

drawings as of circular configuration in cross section for the purposes of illustration. It is preferred, however, that the interior of the bottle neck be of a rectangular configuration in cross section, as shown in Fig. 4 to 60 provide flat sides 8. Also, upon reference to Fig. 1 of the drawings, it will be observed that the bottle neck gradually increases in thickness toward the flat sides 8 so as to provide a maximum thickness, at a point adjacent the outer end of the bottle neck as indicated at 9.

The neck is provided, adjacent its outer end, with diametrically opposite openings which preferably vary in diameter to permit the contents of the bottle to be dispensed in different volume if so desired. Also as is apparent proper venting of the bottle will be permitted by this construction. The larger of the openings has a stopper 10 mounted thereon which may be made of cork or any other suitable material and has a head 11 formed on its outer end which simultaneously engages the outer periphery of the bottle neck. By preference the inner end 70 of the stopper extends inwardly for an appreciable distance beyond the wall 8 through which it passes. A closure 12 is arranged in the opposite opening, this closure being likewise made of cork or other suitable material and having a head 13 formed thereof which engages the periphery of the bottle neck. This stopper likewise has its inner end extended appreciably beyond the inner wall of the side 8 through which it penetrates.

In order to hold the stopper from displacement a retaining rod 14 is provided which is preferably frangible and extends across the bottle neck and through the closures 10 and 13 as shown in Fig. 1. One end 15 of said rod is enlarged to provide a head while the opposite end is smooth to permit penetration of the rod through the bores of the closures 13 and 10, in the order named. 95 The rod preferably carries a key 16 which engages the head 15 for a purpose herein-after described. The end of the rod opposite to that which carries the head 15 preferably extends for a short distance beyond the head of the closure 10 and has a metal washer 17 mounted thereon. The free end of said rod beyond the washer, when subjected to heat, fuses the rod to the washer thereby providing a positive seal between 100 110

the stoppers to prevent removal of the latter until the seal is broken which latter is accomplished by breaking the rod 14.

In use of this device, after the bottle has been filled the closures are mounted therein and sealed in a manner above described. When it is desired to remove the contents of the bottle pressure is exerted upon the key plate 16 so as to break off the head 15 thereby permitting the rod 14 to be withdrawn through the closures 10 and 13. The closures may then be readily removed in an apparent manner and liquid dispensed through either one of the openings formed in the neck of the bottle. It is preferred that the key plate 16 carry the trade-mark of the original manufacturer. Moreover, the bottle may be otherwise suitably marked to reduce possibility of refilling the same, by unauthorized manufacturers, to a minimum. Consequently, although the bottle can be refilled nevertheless it can be done so practically only through the use of especially designed filling means and can be closed likewise only through the use of especial means. Consequently refilling of the bottle by any one other than the original manufacturer, who is equipped with the especial facilities for refilling, is discouraged.

Various changes may be made in this device especially in the details of construction, proportion and arrangement of parts without departing from the spirit and scope of the invention as covered by the appended claims.

It should be understood that the rod 14 may be secured directly to the bottle if so desired, thereby providing the bottle with only one lateral opening through which the rod 14 extends and which receives the closure 12.

What is claimed is:—

1. A bottle including a body closed at both

ends and provided with lateral openings, closures for said openings, and retaining means common to both closures for holding the latter from displacement, said means being frangible to permit simultaneous removal of the closures.

2. A bottle including a neck closed at its outer end and provided with lateral openings, closures mounted in said openings, and a frangible rod connecting said closures substantially as described.

3. A bottle including a neck closed at its outer end and provided with aligning openings, closures arranged in said openings, a frangible rod extending across the neck and engaged with the closures, and means to break said rod to permit removal of the closures.

4. A bottle including a neck having openings therein of unequal diameters, closures arranged in said openings, and means common to all of said closures to prevent displacement thereof.

5. A bottle including a neck having openings of unequal diameter and equipped with closures for the openings, frangible means common to all the closures to prevent removal of the latter, and means to break said frangible means to permit removal of the closures.

6. A bottle including a body closed at both ends and provided with a lateral opening, a closure for said opening, and a breakable retaining means carried by said bottle and engaging said closure for normally holding said closure in a closed position.

In testimony whereof I affix my signature in presence of two witnesses.

WILMOT F. CROZIER.
